DESIGN.

G. M. MINTON.

CIGARETTE HOLDER AND ASH TRAY.

APPLICATION FILED OCT. 21, 1919.

58,927.

Patented Sept. 6, 1921.

Gustave M. Minton, Inventor
By his Attorney, Charles G. Hensley

UNITED STATES PATENT OFFICE.

GUSTAVE M. MINTON, OF NEW YORK, N. Y.

DESIGN FOR A CIGARETTE-HOLDER AND ASH-TRAY.

58,927.

Specification for Design.

Patented Sept. 6, 1921.

Application filed October 21, 1919. Serial No. 332,312. Term of patent 3½ years.

To all whom it may concern:

Be it known that I, GUSTAVE M. MINTON, a citizen of the United States, residing in the city, county, and State of New York, have invented a new, original, and ornamental Design for a Cigarette-Holder and Ash-Tray, of which the following is a specification, reference being had to the accompanying drawing, forming part thereof.

The figure is a perspective view of a cigarette holder and ash tray, showing my new design.

I claim:

The ornamental design for a cigarette holder and ash tray, as shown.

GUSTAVE M. MINTON
